US00D887400S

(12) **United States Design Patent** (10) **Patent No.:** **US D887,400 S**
(45) **Date of Patent:** **** Jun. 16, 2020**

(54) **CROSSOVER FOR RFID IC TERMINALS**(71) Applicant: **Impinj, Inc.**, Seattle, WA (US)(72) Inventor: **Ronald A. Oliver**, Seattle, WA (US)(73) Assignee: **Impinj, Inc.**, Seattle, WA (US)(**) Term: **15 Years**(21) Appl. No.: **29/703,188**(22) Filed: **Aug. 26, 2019****Related U.S. Application Data**

(62) Division of application No. 29/684,465, filed on Mar. 21, 2019, now Pat. No. Des. 865,726, which is a division of application No. 29/590,787, filed on Jan. 13, 2017, now abandoned.

Primary Examiner — John Windmuller(74) *Attorney, Agent, or Firm* — Hertzberg, Turk & Associates, LLC(57) **CLAIM**

The ornamental design for a crossover for RFID IC terminals, as shown and described.

DESCRIPTION

The FIGURE is a plan view of a crossover for RFID IC terminals showing my new design.

All elements of the claimed design are flat and co-planar.
